UNITED STATES PATENT OFFICE.

F WALTER GUIBERT, OF DETROIT, MICHIGAN.

WATER-TUBE BOILER.

1,168,880.

Specification of Letters Patent. Patented Jan. 18, 1916.

Application filed July 11, 1914. Serial No. 850,373.

To all whom it may concern:

Be it known that I, F WALTER GUIBERT, citizen of the United States, residing at Detroit, county of Wayne, State of Michigan, have invented a certain new and useful Improvement in Water-Tube Boilers, and declare the following to be a full, clear, and exact description of the same, such as will enable others skilled in the art to which it pertains to make and use the same, reference being had to the accompanying drawings, which form a part of this specification.

This invention relates to water tube boilers and consists of an arrangement of the tubes to effect a uniform heating of the water of the lower drum. In ordinary water tube boilers the water near the bottom of the lower drum is relatively cold. My invention obviates that condition.

In the drawings: The figure is a vertical cross-section of a furnace and a water tube boiler.

a—a are tubes connecting the lower drum *b* with the upper drum *c*.

d is a furnace provided with a fire pit *e* and a combustion chamber *f*. In the latter are located the tubes and the drums. Those tubes, or some of them, nearest the fire are extended down through the shell of the drum and into the interior to varying depths. The mouths of these extensions are bell-shaped so as not only to assist circulation but also to prevent the lifting of mud, sludge, etc. These extended tubes are terminated at different depths so as to draw water from all levels in the lower drum. It is preferable to extend the tubes into the interior of the drum from the top and sides instead of attaching them lower down on the sides and at the bottom, although similar but less effective results can be accomplished by so attaching them.

Copies of this patent may be obtained for five cents each, by addressing the "Commissioner of Patents, Washington, D. C."

I am aware that tubes have heretofore been extended into the lower drum of a water tube boiler but for a different purpose. 45 The tubes so extended have been used for and adapted only for down flow of the water.

Inasmuch as the tubes that reach the lowest parts of the lower drum are nearest 50 the burning fuel they are in the hottest zone and consequently the water will rise in these and they are the up-going tubes.

What I claim is:—

1. A water tube boiler, having in combination, an upper and a lower drum, and tubes connecting the two drums, a number of the up-going tubes protruding into the interior of the lower drum having their mouths in the lower parts of the lower 60 drum.

2. A water tube boiler, having in combination, an upper drum, a lower drum, and tubes connecting the two drums, a number of the up-going tubes protruding into the 65 interior of the lower drum having their mouths located at different levels in the lower drum from the bottom upward.

3. The combination with a furnace provided with zones of greater and less heat, 70 of a water tube boiler comprising, an upper drum, a lower drum, and tubes connecting the drum, several of the tubes located in the zone of greater heat protruding into the interior of the lower drum having their 75 mouths in the lower portions of the lower drum.

In testimony whereof, I sign this specification in the presence of two witnesses.

F WALTER GUIBERT.
